UNITED STATES PATENT OFFICE.

VICTOR TEODOR JULIN, OF LIDINGON, SWEDEN.

CALIPER GAUGE.

Application filed July 8, 1919. Serial No. 309,498.

To all whom it may concern:

Be it known that I, VICTOR TEODOR JULIN, residing at Skarsatra, Lidingon, Sweden, have invented certain new and useful Improvements in Caliper Gauges, of which the following is a specification.

The present invention refers to a caliper gauge of the type in which the measurement is made between anvils on the legs of a frame.

10 The invention has for its object to establish a sure and rapid adjustment of said anvils.

In the accompanying drawings Fig. 1 is a side view of the caliper gauge partly in section, Fig. 2 is a side view of an inside caliper gauge, and Fig. 3 illustrates in side view partly in section a modified construction.

In Fig. 1, 1 indicates the usual frame, 20 on the one leg of which two tolerance anvils 2, 3 are provided. According to the invention these tolerance anvils are mounted eccentrically on a shaft 4, which can be rotated by means of a head 5 or the like, and 25 be locked in position by a suitable locking device of any known construction. If required only one of the tolerance anvils 2, 3 may be eccentrically mounted on the shaft 4. The anvils 2 and 3 are made fast on 30 shaft 4 in any convenient way so as to turn therewith, the degree of eccentricity and the position to which said shaft is turned on its axis determining the intervals between them and the measure anvil 8. Thus if the 35 shaft be turned till the most eccentric part of the periphery of anvil 2 or 3 is presented opposite measuring anvil 8 the interval will be least, and any other position of the anvil will be proportionately greater. 40 The same is true of both anvils 2 and 3, as is shown, both being eccentric and correspondingly arranged on the shaft 4. The head 5, as shown, consists of a hollow milled cap, pinned to the outer end of shaft 4 and 45 containing a helical spring 17 which bears inwardly against disc 18, mounted on said shaft and fitting into a corresponding recess in the proximate end of the part of frame 1 which serves as a bearing for shaft 4. 50 This disc is preferably free on shaft 4. Said spring 17 will take up any jar incident to operation. It is not, however, indispensable, nor is the form of head. As above indicated, any ordinary head or equivalent 55 means may be substituted for it without affecting the subject matter claimed. The ec-

centricity of the anvils 2 and 3, or one of them, need be but slight.

In the opposite leg of frame 1 a micrometer screw 7 is provided, on the end of which 60 a measure anvil 8 is mounted, which by means of the screw can be carefully adjusted towards the tolerance anvils 2, 3.

By rotating the shaft 4 it is possible to amend the tolerance which is determined by 65 the tolerance anvils 2, 3.

In Fig. 2, 2 and 3 are the tolerance anvils, mounted on the shaft 4, 7 the micrometer screw by means of which a slide or anvil 8 can be adjusted, said slide or anvil being 70 set by means of a screw 9.

The modification illustrated in Fig. 3 substitutes for shaft 4 a micrometer screw 16 having fixed thereon two oppositely presented smooth cones 10 and 11 for adjusting 75 tolerance anvils 2 and 3 bored conically to receive them. These anvils are slidably arranged in recesses of frame 1 and are forced to the left, as viewed in Fig. 3, in contact with the right hand side of the cones 10, 11 by means of springs 12, 13, surrounding the outer part 2^a, 3^a of the anvils and inserted between the inner wall of the recess of the frame 1, in which the anvils are placed, and an outer flange 12^a, 13^a on the 80 anvils. On turning the screw 16 in one direction the cones 10, 11 are moved longitudinally, so that the anvil 2 is moved by the action of spring 12 from the anvil 8^b, whereas simultaneously the other anvil 3 is advanced towards its opposite anvil 8^a, by the 85 action of the cone 11. By turning the screw 16 in the opposite direction of the cones 10, 11 are moved longitudinally in the opposite direction, so that the anvil 3 is moved by 90 the same cone 10 toward the anvil 8^b. In this modification the anvils 2 and 3 do not turn and of course need not be eccentric.

The opposite leg of frame 1 carries a micrometer screw 7, by means of which the 100 anvils 8^a, 8^b, opposed to the anvils 2, 3, may be adjusted simultaneously, as by a cross piece 14, connected with the anvils 8^a, 8^b, which are slidably mounted in the head 15. The cross piece 14 is swivelled at its middle 105 to the end of the micrometer screw 7 by any convenient means of attachment, as for example a clamping nut 19 turned home on a reduced terminal part of said screw, which part passes through said cross piece. As the latter moves inward and outward with the screw 7 and the anvils 8^a and 8^b are carried 110

by said cross piece the two anvils must be equally advanced toward or withdrawn from the tolerance anvils 2 and 3 by turning the screw 7 in one direction or the other.

By means of the device described it is possible to adjust the anvils 2, 3 for the tolerance required and to adjust the anvils 8^a, 8^b for the measure required. The connection between the anvil 8 and the micrometer screw in Fig. 2 is the same as in Fig. 3 and, therefore, need not be further described.

Having thus described my invention, what I claim and desire to protect by Letters Patent is:

1. In combination in a gauge, a frame having two legs, a shaft rotatably mounted in one of said legs, two tolerance anvils 20 mounted on and operable by said shaft, a micrometer screw mounted on the other leg, and a measuring anvil carried by said micrometer screw and cooperating with said tolerance anvils.
2. A gauge comprising two tolerance anvils, an opposed measuring anvil, means for adjusting the latter anvil toward the former anvils, a frame supporting all of said anvils and means whereby said tolerance an-

vils may be adjusted by a single operation 30 for the purpose set forth.

3. A gauge comprising a shaft adapted to be rotated, a tolerance anvil mounted eccentrically on said shaft and adjusted by rotation of said shaft, and measuring means 35 adjustable relatively to said tolerance anvil.

4. A gauge comprising a pair of tolerance anvils, a rotatable shaft for adjusting them and measuring means adjustable toward or from said tolerance anvils.

5. A gauge comprising a rotatable shaft, a pair of tolerance anvils eccentrically mounted on said shaft to turn therewith and measuring means adjustable toward or from said tolerance anvils.

6. A caliper gauge comprising, a frame having two legs, two tolerance anvils mounted in one leg of said frame, a single means for simultaneously adjusting said anvils as to tolerance, and an adjustable measure anvil mounted in the other leg of said frame and opposed to both of said tolerance anvils.

In testimony whereof I have signed my name to this specification.

VICTOR TEODOR JULIN.
